UNITED STATES PATENT OFFICE

2,013,392

CONTAINER

William H. Siemon, Philadelphia, Pa.

Application July 11, 1934, Serial No. 734,655

7 Claims. (Cl. 217—1)

This invention relates to containers, including barrels, and particularly to those made from thin sheet material, like ply wood, fiber sheets, etc.

When making a container body of sheet material, one or more longitudinal joints are necessary, where parts of the sheet come together. These joints are sometimes made as butt joints, having a thin piece or strip of some kind, as sheet metal, lapped over the abutting parts, and are securely fastened thereto by clinched rivets or staples. Some longitudinal joints are formed bylapping the adjoining parts and securely fastening these lapped parts together by clinched rivets or staples, thus eliminating the necessity of using an extra overlapping strip, as with a full length, butt joint. But the ends of such a longitudinal, lapped joint form in the case of a barrel, long, triangular openings, at the barrel heads, permitting a granulated or powdered barrel content to sift through.

One of the objects of my invention is to provide a construction of barrel or container made of sheet material, wherein the longitudinal joint in the body of the barrel or container is mainly of lap formation, terminating at its ends in transformed butt formations at the peripheral zones of the barrel headers, so as to there present a continuous thickness of material next to the periphery of each barrel or container head, and thus avoid any triangular opening at the joint portion adjacent the barrel heads, which would otherwise be formed without resorting to such transformation into a butt portion of joints.

Another object in connection with the transformation of a portion of the lap joint to a butt joint, at the heads, is to strengthen the head ends of the barrel by having a continuity of contact made possible at the butt portions of the joints, between the outside hoop and the two liners, on the opposite sides of each header, which are firmly attached, with the body sheet, to the outside hoop.

A further object of my invention is to provide a sift-proof seal at the change of formation of lap joint to butt joint, by cementing over the cracks, paper or other thin material, suitable for the purpose, or by the formation of a cement film across the cracks.

Another object is to provide with each header disc, an overlapping, sealing sheet, within the barrel and next to each disc, to make the joint sift-proof around the periphery of the disc.

A further object is to strengthen the thin sheet body of a barrel, at one or more zones, between the headers, by means of a stiffening hoop put

next to the inside of the barrel body, to serve as an arch support to the curved thin wall of the barrel, to strengthen the same against an outside impact.

And a further object is to stiffen and strengthen the inside hoop by providing an outside hoop, opposite the inside hoop, fastening together the two hoops, with the barrel body between, by some clinched fastening means, as rivets, nails or staples, forced therethrough.

With these and other objects, which will hereinafter appear, my invention resides in certain construction, one embodiment of which is illustrated in the drawing, and is hereinafter described. Its features are explained, and what I claim is set forth.

In the drawing,

Figure 1 is a perspective view of a barrel or container embodying my invention. Parts are broken away to illustrate the construction.

Figure 2 is an inside view of a joint fragment of the barrel shown in Figure 1.

Figure 3 is an inside view of the same joint structure shown in Figure 2, but exclusive of the header and liners, showing how the lap joint merges into a butt joint, by having a notch in the corner of the inside lap portion, of the longitudinal joint.

Figure 4 shows a similar joint structure to that shown in Figure 3, but has the notch in the corner of the outside lap portion, of the longitudinal joint.

Figure 5 shows the same joint structure illustrated in Figure 4, except it is here shown reversed in position to correspond to the lower part of the longitudinal joint, shown in Figure 1.

Figure 6 is a fragmental mid-section of a barrel, showing the wall distorted and separated from the outer hoop, by an impacting object, in the absence of an arch formed by an inner hoop.

Figure 7 illustrates a section of barrel wall with an inside hoop serving as a supporting arch.

In the figures, the bent sheet 10, forming the barrel or container body may be of any material, including ply-wood, which may be of any number of plies, and is shown in the drawing to be of three-ply wood, having a longitudinal joint 11, with a long portion 12, which is shown to have an outer part 13, overlapping an inner part 14. The parts 13 and 14, being integral with the body sheet 10, are held overlapped together, by clinch fasteners 15, which may be rivets, staples or nails. The upper corner, of the joint part 14, is notched at 16, and the corner 17, of the outer part 13, is bent into the notch 16, so that it presses tight 55

against the horizontal edge 18, of the notch 16, and so that the long edge 19, of the part 13, butts against the vertical edge 20, of the notch 16. The butt joint 21, so formed, is in the zone 5 of the plane, of the header 22, seated upon an inner liner 23, and has a paper disc seal 24, overlapping the header 22, sufficiently to lay next to the periphery of the header 22, and to extend up behind the outer liner 25. The horizontal edge 10 18, of the notch 16, is preferably positioned to come next to, and to be below the inner liner 23. In the same zone with the liners 23 and 25, and the header 22, is an outside hoop 26, wide enough to be properly engaged by clinched fastening means 27, binding together the hoop 26, the outer liner 25, the upstanding part of the paper seal 24 and the body sheet 10, and also the inner liner 23, with the body sheet 10 and the hoop 26. 20

The lower end of the longitudinal joint 11 is shown to have a transformation from a lapped joint portion to a butt joint portion, wherein the notch 28 is made in the lower corner, of the outside joint part 13, and the lower corner of the inside joint part 14 is bent outward, so that it bears against the horizontal edge 29, of the notch 28, and so that the long edge 30, of the inner part 14, butts against the vertical edge 31, of the notch 28. The butt joint 32, so formed, is in the zone 25 of the plane of the lower header 33, associated with liners 23 and 25, outside hoop 26, and paper seal 24, the same as with header 22 at the top of the barrel. It will be noticed in Figure 1, that the horizontal edge 29, of the notch 28, is on top of the lower, of the hoops 26. 30

35

Referring now to the stiffening and strengthening means fixed to the barrel body 10, midway of its length, there are shown two hoops, one marked 34, on the inside, and one marked 35, on the outside, with clinched fasteners 36, binding the hoops and the body wall 10 together. A suitable paper patch, or film of glue or cement covers the cracks about the butt joint transformations and the joints. 40

45 In Figure 6 is shown a wall section fragment marked 10^a, with an outer hoop fragment marked 35^a, with two spaced clinched rivets marked 36^a, in between which, but to one side of the hoop 35^a, is an impacting object, marked 37, shown to have forced the wall section 10^a inward, from the hoop 35^a, between the rivets 36^a, in the absence of an inner hoop, to prevent this distortion. 50

55 In Figure 7 is shown a wall section fragment marked 10^a, with an inner hoop fragment marked 34^a, and two spaced clinched rivets 36^a, in between which, but to one side of the hoop 34^a, is an impacting object, marked 37^a, shown to have been resisted and held against distorting the wall section 10^a, by the arched action of the inner hoop 34^a. Where an outside and an inside hoop 60 are used in the same zone, as 35 and 34 respectively, shown in Figure 1, with clinched fastening means 36, therethrough, the hoop 35, while in itself will resist an outside impact, also will strengthen the inner arching hoop 34, against an inward distortion of the barrel wall body 10. 65

70 While I have shown and described a barrel or container body made of a single sheet of material, obviously the body can be made up circumferentially of a plurality of sheets, having a plurality of longitudinal joints, where one or more of said joints can be similar to the one shown and described, as mainly of lap formation with transformed portions to the butt formation at one or both ends, or at any intermediate point in the 75

zone of an interior or exterior hoop. The transformed butt formation affords a joint portion of continuously uniform thickness, with the other parts of the sheet barrel wall contacted by hoops, liners or headers. Any crack co-incident with the formation of such a butt portion, of joint can be easily sealed over by cementing over the crack a piece of suitable paper, or by covering the crack with a film of cement or glue, as above indicated. 5

The paper sealing disc 24, used to seal the 10 joint at the periphery of the header 22, is enough larger in diameter than the header 22, to be brought up behind the upper liner 25, which, when secured in place by clinched fasteners, binds the peripheral overlap of the paper disc 24 to the 15 barrel body 10.

Relative to the inside hoop 34, its resistance, serving as an arch, to stiffen and strengthen the body wall 10, against distortion by an impacting object 37^a, is illustrated in Figure 7, while in Figure 6, the impacting object 37, is represented as having partly pushed in the wall section 10^a, at a portion which is between the fasteners 36^a, and away from the outside hoop section 35^a. 20

Inasmuch as changes in the one embodiment 25 of my invention herein illustrated and described can be made without departing from the spirit and scope thereof, I wish to include all forms and changes which come within the purview of the following claims. 30

I claim,

1. In a container having a body wall made of sheet material, a longitudinal joint having its parts integral with said body wall, said longitudinal joint comprising adjoining joint portions in 35 the line of said longitudinal joint, one of said joint portions being of overlapped formation, with parts of said body wall overlapping and forming a double thickness of wall at said overlapped formation of joint, another and adjoining joint portion to the overlapped portion, being of butt formation, with parts of said wall in said joint abutting one another, to form a continuity of single thickness of wall across the abutting edges, of the butt formation of joint in said wall. 45

2. In a barrel having a body wall made of sheet material, including a header, and seating means for said header together with an outer hoop in the zone of said header, a longitudinal joint to said body wall, with parts of said joint integral 50 with said body wall, said longitudinal joint including a lapped joint portion of double wall thickness, merged at the zone of said header, into a butt joint portion of a continuous single wall thickness of said body wall across the abutting edges of said butt portion, and engaged between the said header with said seating means on one side, and said outer hoop on the other side, fastening means securing parts of said lap joint portion together and other fastening means for securing said seating means, said body wall and said outer hoop together. 60

3. In a barrel having a body wall made of sheet material, a longitudinal joint having its parts integral with said body wall, a part of said joint having an inside portion, with a joint edge, overlapping an outside portion with its joint edge, there being a notch in the edge of one of said overlapping joint portions, having two relatively transverse notch edges, one of which notch edges 70 is transverse to the notched edge of said joint portion, part of the unnotched edge of the other joint portion being bent into said notch, against the last named notch edge of said notch, to have the extended longitudinal edge of the unnotched 75

joint portion in butt relation to the other notch edge of said notch, forming by such butt relation a butt joint having a continuity of single wall thickness across said joint, and forming, in juxtaposition to a part of said longitudinal joint, a merging therewith.

4. In a barrel having a body wall made of sheet material, a longitudinal joint having its edge parts integral with said body wall, one of said edge parts overlapping the other of said edge parts so that one edge part is on the inside, and the other edge part is on the outside, there being a notch formed in one of said edge parts, having a notch edge in line with the edge of the unnotched extension of the other of the two lapped parts, with the said extension bent into said notch to have its longitudinal edge in butt relation with the said notch edge.

5. In a barrel having a body wall made of sheet

material, an inside hoop next to said body wall positioned to be in a zone intermediate of the ends of said barrel to afford a stiffening compressive arch to said wall.

6. In a barrel having a body wall made of sheet material, an inside hoop and an outside hoop upon said body wall, in the same zone, and fastening means passing through said hoops and said wall to bind the same together.

7. In a barrel having a seating means at one chime end, a header on said seating means, and a liner next to said header on the outer part of said header, a disc of paper or the like next to the under side of said header extending out from the periphery of said header to be bound between said liner and said chime end for sealing purposes.

WILLIAM H. SIEMON.
